UNITED STATES PATENT OFFICE.

OLIVER TILLMAN, OF SAN JOSE, CALIFORNIA, ASSIGNOR TO CHARLES SIMARD, OF SAN JOSE, CALIFORNIA.

BURNER FOR OIL.

SPECIFICATION forming part of Letters Patent No. 708,978, dated September 9, 1902.

Application filed November 18, 1901. Serial No. 82,692. (No model.)

To all whom it may concern:

Be it known that I, OLIVER TILLMAN, a citizen of the United States, residing at San Jose, in the county of Santa Clara and State of California, have invented certain new and useful Improvements in Vaporizers and Burners for Oil, of which the following is a specification.

My invention relates to improvements in vaporizers and burners for oil, the object of my invention being to provide an apparatus of this character which shall be simple in construction and economical in operation.

The device is used for generating steam or for heating or cooking purposes. It is of special utility for kitchen stoves or ranges.

My invention therefore resides in the novel construction, combination, and arrangement of parts for the above ends hereinafter fully specified, and particularly pointed out in the claims.

In the accompanying drawings, Figure 1 is a top plan view of my improved device, certain parts being shown in section. Fig. 2 is a side view of the same. Fig. 3 is an end view of the same.

Referring to the drawings, 1 represents the oil-supply pipe, controlled by the angle-valve 2 and admitted by means of a pipe-section 3 into the interior of a steam-pipe 4. The amount of opening of the oil-pipe into said steam-pipe is regulated by means of the valve 5. (Shown in section in Fig. 1.)

The steam-pipe 6, coming from the steam-drum 7, leads to a point 8, directly beneath the middle of said steam-drum, where it divides into two branches 9, the ends of which are bent around to form nozzles 10, and in order to finely divide and vaporize the oil emerging therefrom said nozzles are filled with wire-gauze, as shown at 11. The oil is thus vaporized by the steam on its emergence from said nozzles and can be burned at the nozzles. The flames and products of combustion impinge upon a spreader 12, which is in the form of a pyramid and rests upon the top of a wa-

ter-supply pipe 13. Said water-supply pipe has three coils resting on the top of a pan 14, the use of said pan being to hold the flames coming from the nozzles and concentrate them upon said water-pipe coils. By this construction the water in said water-pipes is very highly heated, so that it passes by the upright pipe 15 into the end 16 of the steam-drum, where it is exposed to the heat of the flames reflected from the water-pipes and pan 14, and rising up against the under side of said drum, whereby the water in said drum is converted into steam. Steam is first generated by kindling-wood or other suitable material in the pan 14. The drum 7 is supported by bars 17 upon the pan 14.

I claim—

1. The combination of the steam-drum, the water-pipe leading thereto, the pan in which said water-pipe is coiled, the spreader above said pan and below said drum, the steam-pipe issuing from said drum, the oil-supply pipe leading into said steam-pipe, the branch steam-pipes into which the oil and steam flow, and the nozzles terminating said branch pipes and discharging against said spreader, substantially as described.

2. The combination of the steam-drum, the water-pipe leading thereto, the pan in which said water-pipe is coiled, the spreader above said pan and below said drum, the steam-pipe issuing from said drum, the oil-supply pipe leading into said steam-pipe, the branch steam-pipes into which the oil and steam flow, the nozzles terminating said branch pipes and discharging against said spreader, and the wire-gauze in said nozzles, substantially as described.

In witness whereof I have hereunto set my hand in the presence of two subscribing witnesses.

OLIVER TILLMAN.

Witnesses:

M. E. FORD,
H. W. MCCOMAS.
